UNITED STATES PATENT OFFICE.

JAMES H. SEWALL, OF PORTLAND, MAINE, ASSIGNOR TO THE CONSOLIDATED CAR HEATING COMPANY OF WEST VIRGINIA, OF ALBANY, NEW YORK.

CAR-HEATING APPARATUS.

SPECIFICATION forming part of Letters Patent No. 445,090, dated January 20, 1891.

Application filed January 7, 1889. Serial No. 295,647. (No model.)

To all whom it may concern:

Be it known that I, JAMES H. SEWALL, of 5 Portland, county of Cumberland, State of Maine, have invented an Improvement in Car-Heating Apparatus, of which the following description, in connection with the accompanying drawings, is a specification, like letters on the drawings representing like parts.

This invention has for its object to improve 10 the construction of apparatus employed for heating cars.

The invention herein shown is an improvement on the car-heating apparatus invented by John B. Porter, yet is applicable to other 15 heating apparatus wherein two heaters are employed to heat the water for a common set of circulation-pipes.

In car-heating apparatus of the kind referred to comprising a set of water-circulation pipes within the car and two heaters for 20 heating the same independently or simultaneously at will valves have been interposed between the heaters, so as to control the water in its passage.

In accordance with this invention a simple 25 device is provided in lieu of such valves, which requires no attention and which simply gives direction to the current, thereby accomplishing the desired end.

The device herein shown for giving direction to the current comprises a shell or case 30 having a passage through it from end to end and a pipe leading into said shell at one side or formed integral with it, said pipe being 35 bent or formed at a right angle, so that water passing through the pipe will be directed in the direction to which said pipe is turned, yet at the same time a free passage is afforded for the water directly through the shell.

Figure 1 shows in elevation and partial section a car-heating apparatus provided with a director for the warming-liquid embodying this invention; Fig. 2, a vertical section of the director on a larger scale; Fig. 3, a plan 45 view of the controlling-valve of the car-heating apparatus.

The car-heating apparatus herein shown, to which my invention is applied, comprises a system of water or other liquid-circulating 50 pipes *a*, an expansion-chamber *b*, and two

heating-coils or communicating portions of the piping *c d*, one of the said coils being contained in a heater *d'*, (see dotted lines,) in which a fire may be kindled, and the other coil, as *d*, being contained in a suitable inclosing case *d''*, into which steam is admitted by a pipe *e*, leading from a main steam-pipe *e'*. The coils *c d* are joined to the circulating-pipes *a* at the lower end by a T-coupling *f*, and at the upper end by a current-director *g*. (Best shown in Fig. 2.) The current-director *g* comprises a shell or case having a passage *g'* through it, and a curved pipe *g''* is contained within the shell or case, being formed integral therewith, said pipe having 65 an inlet at one side of the shell or case and bent up within and parallel to said passage to form an outlet considerably above said inlet.

In operation, the water heated, for instance, 70 in the coil *c* passes upwardly through the passage *g'* of the shell or case *g* to the expansion-tank, thence through the circulating-pipes returning to the coil, and when the coil *d* is heated the liquid passes upwardly 75 through the curved pipe *g''* to the expansion-drum, thence through the circulating-pipes, returning to the coil *d*; or both coils may be simultaneously heated and the liquid contained therein passed through the current-director. By the employment of a current-director the liquid rising from the coil *d* will not 80 circulate through the coil *c*, and thereby short-circuit the circulation-pipe, or vice versa, as the direction given it by the upturned end of 85 the pipe *g''* is sufficient to cause it to flow upward to the expansion-drum *b*; also it will be seen that a current-director fulfills all the requirements, cannot get out of order, and requires no attention whatever. 90

I do not desire to limit myself to the use of the current-director to the particular system of car-heating apparatus herein shown, as any independent arrangement or location of the heaters *c* and *d* may be employed and 95 the function and operation of the current-director remain the same.

I claim—

1. In a car-heating apparatus, a system of 100 circulating-pipes within the car and two in-

dependent heaters, both in operative contact with said circulating system, adapted to be operated simultaneously or separately by heat imparted thereto, combined with a current-director interposed at the junction or point of contact of the said heaters and circulating system, substantially as described.

2. In a car-heating system, the combination, with a system of water-circulating pipes within the car, of a suitable radiator in contact with said circulating system, mechanism for supplying the said radiator with steam as a primary means of heating said circulating system, and a secondary independent heater also in operative contact or connected with said circulating system and adapted to heat the same, combined with a current-director, substantially as described, interposed at the junction or point of contact of the primary and secondary heaters, and the circulating-pipes, substantially as described.

3. In a car-heating system, the combination, with a system of circulating-pipes within the car and two independent heaters in operative contact with said circulating system, each

having exposed radiating-surfaces, one of the said heaters being adapted to contain a fire and the other to receive steam, combined with a current-director, substantially as described, located at the point of contact or junction of the said heaters and circulating system, substantially as described.

4. In a car-heating apparatus, the circulating system located within the car and having an expansion-drum, two independent receptacles containing the circulating-pipes connected at each end with the circulating system, a steam-receiving case inclosing one of the said receptacles, combined with a current-director located at the junction of the upper end of the said receivers, and the circulating system, substantially as and for the purposes set forth.

In testimony whereof I have signed my name to this specification in the presence of 45 two subscribing witnesses.

JAMES H. SEWALL.
